AUTOMATIC AUTOMOBILE DOOR CATCH
AND LOCKWilliam J. Daningburg, Stamford, Conn., assignor
of one-fourth to Paul Mulnard, Ridgewood,
N. Y.Refiled for abandoned application Serial No.
574,553, November 12, 1931. This application
April 14, 1936, Serial No. 74,281

6 Claims. (Cl. 70—29)

This invention relates to a new and useful improvement in an automatic automobile door catch and lock.

This application is a refile of my original application filed November 12, 1931, Serial No. 574,553.

The invention has for an object the construction of a catch lock, which is characterized by the provision of pivotal handles on the outer and inner sides of the door and capable of operating the bolt of the lock.

As another object of this invention, it is proposed to arrange a key lock upon the door in a manner so that its bolt can restrict the pivoting of the handle on the outer side of the door, for the purpose of preventing opening of the door lock from the outside.

Furthermore, this invention contemplates means associated with the handle on the inside of the door for holding the door lock opened, or for locking the lock so that it cannot be operated by the handle on the outside of the door.

The invention has for a still further object the construction of an automatic automobile door catch and lock, which is of simple, durable construction, desirable in use and efficient in action, and which may be manufactured and sold at a reasonable cost.

For further comprehension of the invention, and of the objects and advantages thereof, references will be had to the following description and accompanying drawing, and to the appended claims in which the various novel features of the invention are more particularly set forth.

In the accompanying drawing forming a material part of this disclosure:—

Fig. 1 is a fragmentary elevational view of a door provided with a lock according to this invention, and viewed from the outside.

Fig. 2 is a fragmentary enlarged sectional view taken on the line 2—2 of Fig. 1.

Fig. 3 is a sectional view taken on the line 3—3 of Fig. 2.

Fig. 4 is an elevational view looking in the direction of the arrows 4—4 of Fig. 2.

The reference numeral 10 indicates a door which is capable of closing against a door jamb 11. The door is provided with a catch lock which includes a retractable bolt 12, capable of engaging in a keeper 13, mounted upon the jamb 11. A recess 14 is formed in the jamb 11, to better accommodate the bolt 12 in its extended position.

The lock upon the door consists of a hollow

casing 15. The casing 15 extends through the door, so that it has a face exposed on the outside, and another face on the inside of the door. A disk 17 is rotatively mounted within the casing. The bolt 12 is pivotally attached at its inner end 18, upon the disk 17.

A pair of rods 19 is pivotally mounted upon the disk 17 and slidably supported by standards 20. One of the rods 19 is adapted to extend from the front face of the casing 15, and the other from the rear face.

Handles 21 are pivotally mounted upon lugs 22 on the outer and inner sides of the casing 15. Cams 23 are integral with the handles 21, and extend through openings 24, partially within the casing 15. The cams are so designed that when the handles 21 hang freely downwards, the rods 19 may assume extended positions in which the disk 17 holds the bolt 12 engaged in the keeper 13. Resilient means in the form of springs 25 are between the disk 17 and the casing 15 to urge the disk into the position in which the bolt 12 is extended. The cams 23 are of such design that when the handles are swung upward to horizontal position, they engage against the rods and cause turning of the disk 17, which in turn, moves the bolt 12.

The lock 26 is mounted upon the outer face of the door 10, and is provided with a bolt 27, capable of extending behind the cam 23, so as to restrict swinging of the outer handle 21. The details of this lock will not be given, since any conventional lock may be used which has an extendable bolt. The handle 21 on the inside of the door, in addition to being pivotally mounted, is also slidably mounted upon its supporting pintle pin 28. Resilient means in the form of a spring 29 coaxially upon the pintle pin 28 serves to urge the handle against one of the lugs 22. A bottom stop 30 projects from this lug and limits downward motion of the handle to the vertical. A second stop 31 projects from this lug 22, and limits the upward motion of the handle to the horizontal.

A finger 32 projects from the cam 23 of the handle upon the inside of the door, and is capable of passing through an opening in the adjacent rod 19, when the handle 21 is pivoted further backwards than allowed by the stop 30. Such pivoting is possible by first moving the handle 21 laterally against the action of the spring 29, so that it may pass the stop 30. When released, the spring 29 urges the handle back against the lug, so that it may maintain its new position. In the new pivoted position, the finger 32 engages in the

opening 33, and latches the rod 19 against motion, to prevent turning of the disk 17 by operating the handle 21 on the free side of the door. The opening 33 must be of sufficient size to allow engagement by the finger 32, even though the handle 21 is moved laterally.

The operation of the catch lock may be understood by assuming it in the condition illustrated in Fig. 2. The bolt 12 is shown in the keeper 13, the bolt 27 is shown to prohibit operation of the outer handle 21, and the other handle 21 is free to be moved. In this condition, a person from the outside of the door cannot cause opening of the lock. A person from the inside may move the handle 21, to cause retraction of the bolt 12, so that the door may be opened. If the lock 26 is operated so that the bolt 27 is drawn in, then the handle 21 on the outside of the door can be operated to cause its cam 23 to depress the rod 19, which, in turn, causes retraction of the bolt 12, so that the door may be opened.

A person at the inside of the door, if he so elects, may place the handle 21 beneath the stop 30, so as to lock motion of the rod 19, and consequently hold the bolt 12 within the keeper, irrespective of attempted opening of the door from the outside, even though the lock 26 has its bolt withdrawn. If a person behind the door so elects, he may move the handle 21 above the stop 31, so that it maintains this position, in which the rod 19 is depressed, the disk 17 is in a turned position, and the bolt 12 is retracted.

It is to be understood that while my invention is described to be an automobile door lock, it may be equipped on any house, garage or other doors.

While I have described my invention with some degree of particularity, I realize that in practice various alterations therein may be made. I therefore reserve the right and privilege of changing the shape of the handle and the form of all other details or otherwise altering the arrangement of the correlated parts without departing from the spirit or the scope of the appended claims.

Having thus described my invention, what I claim as new, and desire to secure by United States Letters Patent is:—

1. A door catch and lock, comprising a casing for attachment upon a door and extending from the inside to the outside of the door, a disk rotatively mounted within the casing, a bolt pivotally mounted on the edge of the disk and extending from the casing for engagement within a keeper of a door jamb, a pair of rods pivotally mounted upon said disk and slidably supported in and extending from the inner and outer sides of said casing, handles pivotally mounted upon the inner and outer sides of said casing, one of said rods having an opening, cams upon said handles extending through openings in the casing to the interior and in line with the free ends of said rods, resilient means urging said disk to project the bolt to its extended position, a lock with an extendible bolt for engaging behind the cam of the handle on the outside of the casing, the handle upon the inside of the casing being also slidable, resilient means for sliding said latter mentioned handle in one direction, stop lugs for normally limiting swinging motion of said handle beyond said limits but allowing swinging motion of the handle when drawn against the resilient means, and a finger upon the cam carried by the handle located on the inside of the door and capable of engaging an opening in one of said rods.

2. An automatic automobile door catch and lock, comprising a casing for attachment upon a door

and extending from the inside to the outside of the door, a disk rotatively mounted within the casing, a bolt pivotally mounted on the edge of the disk and extending from the casing for engagement within a keeper of a door jamb, a pair of rods pivotally mounted upon said disk and slidably supported in and extending from the inner and outer sides of said casing, one of said rods having an opening, handles pivotally mounted upon the inner and outer sides of said casing, 10 cams upon said handles extending through openings in the casing to the interior and in line with the free ends of said rods, resilient means urging said disk to project the bolt to its extended position, a lock with an extendible bolt for engaging 15 behind the cam of the handle on the outside of the casing, the handle upon the inside of the casing being also slidable, resilient means for sliding said latter mentioned handle in one direction, stop lugs for normally limiting swinging motion 20 of said handle but allowing swinging motion of the handle beyond said limits when drawn against its resilient means, and a finger upon the cam carried by the handle located on the inside of the door and capable of engaging an opening in one 25 of said rods, standards within the casing serving to slidably support said rods.

3. An automatic automobile door catch and lock, comprising a casing for attachment upon a door and extending from the inside to the outside of the door, said casing having external lugs on its opposite faces, a disk rotatively mounted within the casing, a bolt pivotally mounted on the edge of the disk and extending from the casing for engagement within a keeper of a door jamb, 30 a pair of rods pivotally mounted upon said disk and slidably supported in and extending from the inner and outer sides of said casing, one of said rods having an opening, handles pivotally mounted upon the inner and outer sides of said casing, 35 cams upon said handles extending through openings in the casing to the interior and in line with the free ends of said rods, resilient means urging said disk to project the bolt to its extended position, a lock with an extendible bolt for engaging 40 behind the cam of the handle on the outside of the casing, the handle upon the inside of the casing being also slidable, resilient means for sliding said latter mentioned handle in one direction, stop lugs for normally limiting swinging motion 45 of said handle but allowing swinging motion of the handle beyond said limits when drawn against its resilient means, and a finger upon the cam carried by the handle located on the inside of the door and capable of engaging an opening in one 50 of said rods, said handles being mounted upon lugs projecting from the faces of said casing.

4. An automatic automobile door catch and lock, comprising a casing for attachment upon a door and extending from the inside to the outside of the door, a disk rotatively mounted within the casing, a bolt pivotally mounted on the edge of the disk and extending from the casing for engagement within a keeper of a door jamb, a pair of rods pivotally mounted upon said disk 60 and slidably supported in and extending from the inner and outer sides of said casing, one of said rods having an opening, handles pivotally mounted upon the inner and outer sides of said casing, cams upon said handles extending through 65 openings in the casing to the interior and in line with the free ends of said rods, resilient means urging said disk to project the bolt to its extended position, a lock with an extendible bolt for engaging 70 behind the cam of the handle on the outside of the casing, the handle upon the inside of the casing being also slidable, resilient means for sliding said latter mentioned handle in one direction, stop lugs for normally limiting swinging motion of said handle beyond 75 said limits but allowing swinging motion of the handle when drawn against the resilient means, and a finger upon the cam carried by the handle located on the inside of the door and capable of engaging an opening in one of said rods.

side of the casing, the handle upon the inside of the casing being also slidable, resilient means for sliding said latter mentioned handle in one direction, stop lugs for normally limiting swinging motion of said handle but allowing swinging motion of the handle beyond said limits when drawn against its resilient means, and a finger upon the cam carried by the handle located on the inside of the door and capable of engaging an opening in one of said rods, the resilient means for urging said handle laterally comprising a spring acting on said handle.

5. An automatic automobile door catch and lock, comprising a casing for attachment upon a door and extending from the inside to the outside of the door, a disk rotatively mounted within the casing, a bolt pivotally mounted on the edge of the disk and extending from the casing for engagement within a keeper of a door jamb, a pair 10 of rods pivotally mounted upon said disk and slidably supported in and extending from the inner and outer sides of said casing, one of said rods having an opening, handles pivotally mounted upon the inner and outer sides of said 15 casing, cams upon said handles extending through openings in the casing to the interior and in line with the free ends of said rods, resilient means urging said disk to project the bolt to its 20 extended position, a lock with an extendible bolt for engaging behind the cam of the handle on the outside of the casing, the handle upon the inside of the casing being also slidable, resilient 25 means for sliding said latter mentioned handle in one direction, stop lugs for normally limiting swinging motion of said handle but allowing swinging motion of the handle beyond said limits when drawn against its resilient means, and a 30 finger upon the cam carried by the handle located on the inside of the door and capable of engaging an opening in one of said rods, the inside stop lug limiting downward motion of the handle to the vertical, and another upward motion to the 35 horizontal.

finger upon the cam carried by the handle located on the inside of the door and capable of engaging an opening in one of said rods, the resilient means for urging said handle laterally comprising a spring acting on said handle.

6. An automatic automobile door catch and lock, comprising a casing for attachment upon a door and extending from the inside to the outside of the door, a disk rotatively mounted within the casing, a bolt pivotally mounted on the edge 10 of the disk and extending from the casing for engaging within the keeper of a door jamb, a pair of rods pivotally mounted upon said disk and slidably supported in and extending from the inner and outer sides of said casing, one of said rods having an opening, handles pivotally mounted upon the inner and outer sides of said 15 casing, cams upon said handles extending through openings in the casing to the interior and in line with the free ends of said rods, resilient 20 means urging said disk to project the bolt to its extended position, a lock with an extendible bolt for engaging behind the cam of the handle on the outside of the casing, the handle upon the inside of the casing being also slidable, resilient 25 means for sliding said latter mentioned handle in one direction, stop lugs for normally limiting swinging motion of said handle but allowing swinging motion of the handle beyond said limits when drawn against its resilient means, and a 30 finger upon the cam carried by the handle located on the inside of the door and capable of engaging an opening in one of said rods, the inside stop lug limiting downward motion of the handle to the vertical, and another upward motion to the 35 horizontal.

WILLIAM J. DANINGBURG.
